(57) **CLAIM**

We claim, the ornamental design for a fluidodynamic actuator, as shown and described.

DESCRIPTION

FIG. 1 is a perspective view of a fluidodynamic actuator, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, taken from below;

FIG. 9 is a perspective view of the fluidodynamic actuator in another embodiment;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a perspective view thereof, taken from below;

FIG. 17 is a perspective view of the fluidodynamic actuator in another embodiment;

FIG. 18 is a front view thereof;

FIG. 19 is a rear view thereof;

FIG. 20 is a left side view thereof;

FIG. 21 is a right side view thereof;

FIG. 22 is a top view thereof;
